US00D740405S

(12) **United States Design Patent**
Yamaguchi

(10) **Patent No.:** **US D740,405 S**
(45) **Date of Patent:** **** Oct. 6, 2015**

(54) **CATALYST CARRIER FOR GAS PURIFICATION**

(71) Applicant: **NGK Insulators, Ltd.**, Nagoya (JP)

(72) Inventor: **Takaya Yamaguchi**, Nagoya (JP)

(73) Assignee: **NGK Insulators, Ltd.**, Nagoya-Shi (JP)

(**) Term: **14 Years**

(21) Appl. No.: **29/460,958**

(22) Filed: **Jul. 17, 2013**

(51) LOC (10) Cl. **23-04**

(52) U.S. Cl.

(57) **CLAIM**

The ornamental design for a catalyst carrier for gas purification, as shown and described.

DESCRIPTION

FIG. 1 is a perspective view of a catalyst carrier for gas purification illustrating my new design;

FIG. 2 is a front view thereof;

FIG. 3 is a top view thereof, the bottom view thereof being a mirror image;

FIG. 4 is a right side view thereof, the left side view thereof being a mirror image;

FIG. 5 is an enlarged partial front view thereof;

FIG. 6 is a cross-sectional view taken through line 6-6 of FIG. 2; and,

FIG. 7 is a middle omitted cross-sectional view taken through line 7-7 of FIG. 5.

The broken lines in the drawings depict unclaimed subject matter only and form no part of the claimed design.
